CLAIM

The ornamental design for a tool for crimping a rigid coupling on a flexible hose, as shown and described.

DESCRIPTION

FIG. 1 is a front elevational view of a tool for crimping a rigid coupling on a flexible hose showing my new design, the undisclosed rear elevational view being a mirror image of the front elevational view;

FIG. 2 is a top plan view thereof;

FIG. 3 is a left side elevational view thereof;

FIG. 4 is a right side elevational view thereof; and

FIG. 5 is a bottom plan view thereof.
